(57) **CLAIM**

I claim the ornamental design for a bike with flywheel cover, as shown and described.

DESCRIPTION

FIG. 1 is a front, top, right side perspective view according to a first embodiment of my design for a bike with flywheel cover.

FIG. 2 is a front view of the bike with flywheel cover shown in FIG. 1.

FIG. 3 is a rear view of the bike with flywheel cover shown in FIG. 1.

FIG. 4 is a right side view of the bike with flywheel cover shown in FIG. 1.

FIG. 5 is a left side view of the bike with flywheel cover shown in FIG. 1.

FIG. 6 is a top view of the bike with flywheel cover shown in FIG. 1; and,

FIG. 7 is a bottom view of the bike with flywheel cover shown in FIG. 1.

The broken lines represent unclaimed portions of the article, and form no part of the claimed design.
